MATERIAL COLLECTING AND LOADING APPARATUS

Thomas K. Andersen, West New Brighton, and Tengel Andersen, Port Richmond, N. Y., assignors to Overhead Loader Corporation, Staten Island, N. Y., a corporation of New York

Application December 11, 1939, Serial No. 308,610

9 Claims. (Cl. 37—144)

This invention is a continuation in part of our prior application Serial No. 148,740, filed June 17, 1937, now Patent No. 2,182,781, and is directed to the novel combination in which the raising and lowering movements of a power-driven weight (usually a digging and collecting bucket) located at one end of a tractor or other self-propelled vehicle and swinging in an arcual overhead path along the fore and aft center line of the tractor, are utilized to oppositely actuate a material-moving implement (as a bulldozer) located at the other end of the tractor.

According to my invention, the bucket functions as an actuator for the bulldozer, the bulldozer being forced down to its work by applying the lifting power to the bucket, and being lifted away from its work when the bucket is lowered by the overbalance of the bucket. This makes it unnecessary to provide any other power actuating mechanism for the bulldozer, with resultant simplicity of construction and saving in installation and maintenance costs, as well as insuring fast, accurate control of the bulldozer.

All the horsepower of the tractor is available to lower the bulldozer, thus insuring ample down pressure on the bulldozer as the bucket is lifted. Moreover, the weight of the counterbalancing bucket and the length of its arms are so proportioned to the weight of the bulldozer and the length of its arms that when the bulldozer is lifted, the tractor balances at approximately the center of its tracks.

The conventional tractor is designed to balance at the center of its tracks and when a conventional bulldozer is hung on the tractor, the weight thereof is concentrated on the front lower track rolls causing rapid wear thereon and necessitating frequent repairs thereto.

In our construction, where the lifting of the bulldozer at the front of the tractor is accomplished by the overbalance of the bucket at the rear of the tractor, such overbalance so nearly equals the overhanging weight of the bulldozer at the front that the tractor still balances at approximately its normal position at the fore and aft center of the tractor tracks. Thus the weight of bucket and bulldozer is properly centered and divided between all of the lower track rolls, which is the way the tractor was designed to function.

Specifically our bucket-bulldozer attachment for tractors comprises a pair of bucket supporting arms pivoted adjacent the sides of the tractor and carrying the bucket at their outer ends and a pair of oppositely pointing bulldozer supporting arms pivoted adjacent the sides of the tractor

at points separate from the pivot points of the bucket arms and carrying the bulldozer at their outer ends. In order to swing the bucket and its arms in its arcual overhead path we provide a power take-off from the tractor motor and power-transmitting connections therefrom to the bucket arms, and in order to apply the lifting (or lowering) movement of the bucket as it travels through said arcual path as lowering (or lifting) movement to the bulldozer, we interpose motion-transmitting linkage between the bucket and bulldozer arms.

We also provide quick-detachable connections which enable the bulldozer to be readily assembled to and disassembled from the tractor with the minimum effort and in the minimum time.

In making such change it is only necessary to insert or remove two bolts and their cotter pins.

Thus we combine, in a single machine, bucket and bulldozer attachments which enable us both to dig and grade on the same dirt-moving job. Our bucket-bulldozer attachment for tractors requires only one investment and only one move of the machine from job to job, and inasmuch as we avoid expensive duplication of operating controls for the bulldozer, the tractor owner can use his tractor equally as well for both digging and grading without materially increasing the cost of the machine over and above the cost of the bulldozer.

In the accompanying drawing:

Fig. 1 is a side elevation of a tractor of conventional type equipped with bucket and bulldozer attachments in accordance with our invention, the bulldozer being shown in full lines as pressed downwardly to the work when the bucket is raised (see full line position of bucket) and being shown in dotted lines as raised from the work when the bucket is lowered (see dotted line position of bucket).

Fig. 2 is a perspective view of the bulldozer detached from the tractor and as seen from the rear.

Fig. 3 is a fragmentary side detail at the attaching end of one of the bulldozer arms, and showing in dotted lines the position assumed by the retaining latch when the bolt therefor is withdrawn to permit the bulldozer to be detached from the tractor, and

Fig. 4 is a fragmentary perspective view of motion-transmitting links which are interposed between the bucket and bulldozer arms.

For the purposes of this application we have shown our invention as applied to a crawler tractor of conventional type, although it will be

understood that the invention may be applied to other self-propelled vehicles, as wheel tractors, trucks or the like.

We have indicated generally at 10 and 11, 5 respectively, the tractor frame and its sub-frame. The side members of the sub-frame are so attached to the tractor frame at its forward end that the sub-frame is supported rigidly in line with the tractor frame which carries the tractor 10 motor. The rear end of the sub-frame is attached to the track frames of the tractor adjacent points 12 located on each side of the tractor at the common center around which both the tractor tracks 13 and the tractor frame oscillate 15 in a vertical plane independently of each other.

As a result of this construction the sub-frame will follow the movement of the tractor frame around the common center of oscillation 12 without hampering the free and independent oscillation 20 of the tractor tracks or the movement of the tractor frame upon its springs.

Pivoted at their inner ends as at 14 to the sides of the tractor is a pair of rearwardly extending bucket supporting arms 15 carrying at 25 their outer ends a bucket 16 of any desired construction. The arms 15 are of such shape and length as to carry the bucket from digging or loading position at one end of the tractor, here shown as the rear end, in an arcual overhead 30 path along the fore and aft center line of the tractor past the pivot points of said arms, to a forward dumping position.

The bucket is swung from loading to dumping position, and vice versa, by any suitable mechanism 35 operated from the tractor motor and is suitably controlled in its travel at all times.

Such mechanism is specifically set forth in our prior application aforesaid and inasmuch as it forms no part of the present invention will be referred to herein only in general terms. Such 40 mechanism includes a winch W mounted on the tractor sub-frame in advance of the motor. Fast to the drum of the winch is a bucket control cable C. This cable passes over suitable 45 guide sheaves on the tractor roof and is made fast at its other end to the bucket. The winch is driven from the tractor motor by any suitable power take-off. The application of power to the winch is controlled by a clutch lever L, and a suitable brake is provided for optionally arresting the travel of the bucket at any selected 50 point when the clutch is disengaged. If the bucket is provided with a latched cover, as is the case with buckets for certain special uses, a suitable latch-tripping mechanism is provided 55 whereby the cover may be released as the bucket approaches dumping position. The clutch lever, brake lever and control for the latch-tripping mechanism are all located conveniently to the operator's reach and near enough to the rear of 60 the vehicle to permit the operator, when manipulating said controls, to have unobstructed vision of the bucket when it is in low loading position.

The location of the power take-off and winch 65 forwardly of the tractor motor utilizes the weight of these parts as a counterbalance against the tractor tipping up in front when the bucket is breaking out its load at the rear.

Detachably pivoted at their inner ends as at 70 17 to the sides of the tractor at pivot points 75 separate from the pivot points 14 is a pair of bulldozer supporting arms 18 carrying at their outer ends a bulldozer 19 of conventional type. The arms 18 are of such shape and length as to position the bulldozer 19 beyond the forward

end of the tractor for limited movement in a vertical arc between the ground and some point high enough above the ground to permit the bulldozer to clear the ground when desired.

According to our invention, motion transmitting connections are interposed between the two sets of arms 15 and 18 for transmitting the motor power of the tractor applied through the bucket arms 15 in lifting the bucket to the bulldozer arms 18 as power to press the bulldozer down- 10 wardly to its work. They also permit the bucket, which at the rear of the tractor nearly equals the overhung weight of the bulldozer at the front of the tractor, to raise the bulldozer from its work when the power is disconnected and the 15 bucket drops by gravity but under the manual control of the operator.

These motion-transmitting connections may be of any suitable type. In their simplest form, and as here shown, the bucket arms 15 are provided adjacent their pivots 14 with short arms 20, here shown as triangular plates. Pivoted at 21 to the forward portions of the plates 20 are links 22, the forward ends of which are pivoted as at 23 to the bulldozer 19.

These links may be either rigid or telescopic. As shown, they are telescopic and provided with a pin 24 to be selectively entered in any of a series of holes 25 (see Fig. 4) for adjusting their effective length so that the relation of the height 30 of the bucket arms to that of the bulldozer arms may be varied at will. This is important when the tractor is at work near a bank which is located closely behind the bucket, or near an arch where there is insufficient head-room for 35 the bucket.

In order to provide for quick detachable connection of the bulldozer arms 18 with the vehicle, the pivots 17 are constructed as spool-like pins (see Fig. 2). Pivoted as at 26 to brackets 27 depending from the side members of the tractor sub-frame (see Fig. 2) are appropriately shaped gravity latches 28 which are removably fastened at their upper ends to said brackets 27 by means of withdrawable pins 29 and cotter 45 pins 30 or their equivalents.

Thus, to attach the bulldozer, it is simply necessary to drive the tractor into the space between the bulldozer arms 18 until the pins 17 are in position to enter the latches, withdraw 50 the bolts 30 and permit the latches 28 to fall to the dotted line position of Fig. 3, lift the free ends of the arms until the pins 17 are within the latches, swing the latches up beneath the pins, and replace the bolts to again hook the 55 latches.

To disconnect the bulldozer, the latches are unhooked to release the pins 17, after which the tractor is backed away from the bulldozer.

By pivoting the bucket and bulldozer carrying 60 arms at separate points, we can change the leverage between said arms whenever required and thus change the speed of lift of the bucket. Best results are obtained when the separate pivots are located in different vertical and horizontal planes, 65 but this is not absolutely essential.

Although we have shown and described the tractor attachments as a bucket and a bulldozer, respectively, it is to be understood that the invention is not limited to the use of these specific 70 attachments. For example, a simple counter-weight may be employed in lieu of a bucket or the bucket may be a shovel, scoop, fork or the like, depending upon the nature of the work and the particular material, as dirt, coal, snow, etc. in 75

which it is to work. Likewise the bulldozer may be any bladed implement, as an angledozer, scraper, snowplow blade or the like depending on the nature of the work and the particular material in which it is to work.

5. What we therefore claim and desire to secure by Letters Patent is:

1. In combination with a self-propelling tractive vehicle, a pair of weight-supporting arms pivoted adjacent the sides of said vehicle, a weight mounted at the outer ends of said arms, means for lifting, lowering, and stopping the movement of the weight-supporting arms, a pair of oppositely pointing secondary arms pivotally connected adjacent the sides of the vehicle at points separate from the pivot points of the weight-supporting arms, a material moving implement attached to the outer ends of said secondary arms, and motion transmitting connections interposed between and pivotally connected to the two sets of arms for depressing the material moving implement when the weight is lifted and for raising said implement when said weight is lowered.
10. 2. The combination of claim 1 in which the weight-supporting arms include short arms extending therefrom near the pivots thereof, and the motion transmitting connections comprise links pivotally attached at their rear ends to said short arms and at their forward ends to said material moving implement.
15. 3. The combination of claim 1, the motion transmitting connections being adjustable in length so that the relation of the height of the weight-supporting arms to the height of the implement-supporting arms may be varied.
20. 4. The combination of claim 1, the inner ends of one pair of arms overlapping the inner ends of the other pair of arms.

5. The combination of claim 1, the pivots for one pair of arms being located in a different vertical plane from those of the other pair of arms.

6. The combination of claim 1, the pivots for one pair of arms being located in a different horizontal plane from those of the other pair of arms.

7. In combination with a self-propelling tractive vehicle, a counterweight and a material-moving implement pivotally connected to the sides of said vehicle at points separate from each other and occupying operating positions at the respective ends of the vehicle, means for swinging the counterweight in an arcual overhead path relative to the vehicle, and motion-transmitting connections between said counterweight and implement for depressing the implement when the counterweight is lifted and for raising the implement when the counterweight is lowered.

8. The combination of claim 7, the vehicle being a tractor, and the overbalance of the counterweight at one end of the tractor substantially equaling the overhung weight of the material-moving implement at the opposite end of the tractor so that when the implement is lifted the tractor balances at substantially the fore and aft center of the tractor tracks.

9. The combination of claim 1, the motion transmitting connections comprising a link pivotally connected at one end to a weight-supporting arm and at its other end to a corresponding implement supporting arm at points spaced from the pivot points of said arms to the sides of the vehicle.

THOMAS K. ANDERSEN. 35
